US0D1063654S

(12) **United States Design Patent** (10) **Patent No.:** **US D1,063,654 S**
(45) **Date of Patent:** **** Feb. 25, 2025**

(54) **SENSOR**

(71) Applicant: **Myocene**, Liège (BE)

(72) Inventors: **Pierre Rigaux**, Liège (BE); **Jean-Yves Mignolet**, Momalle (BE)

(73) Assignee: **MYOCENE**, Liège (BE)

(**) Term: **15 Years**

(21) Appl. No.: **29/811,894**

(22) Filed: **Oct. 18, 2021**

(30) **Foreign Application Priority Data**

Jul. 14, 2021 (EM) 008595946-0001

(51) **LOC (15) Cl.** **10-04**

(52) **U.S. Cl.**

USPC **D10/83**; D24/186

(58) **Field of Classification Search**

USPC D10/46, 83, 85; D24/186

CPC A61B 5/224; A61B 2562/0261; A61B 2503/10; A61B 5/1107; A61B 5/4519; A61B 5/6828; A63B 2024/0065; A63B 2230/60

(57) **CLAIM**

The ornamental design for a sensor as shown and described.

DESCRIPTION

FIG. 1 is a top perspective view of a sensor showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets
